United States Patent Office

Des. 227,662
Patented July 10, 1973

227,662

SHELTER

Bertram S. Warshaw, Miami, and R. William Clayton,
Fort Lauderdale, Fla., assignors to Transportation
Terminals of America, Inc., Miami, Fla.

Filed Nov. 30, 1971, Ser. No. 203,502

Term of patent 14 years

Int. Cl. D25—99

U.S. Cl. D13—1 D

FIG. 1

FIG. 2

FIG. 3

FIG. 4

FIG. 5

FIG. 6

FIG. 1 is a perspective view of a shelter of our invention:

FIG. 2 is a side elevation view thereof, the side not shown being identical to the side shown;

FIG. 3 is a front view thereof;

FIG. 4 is a bottom view thereof;

FIG. 5 is a top plan view thereof; and

FIG. 6 is a rear elevational view thereof.

We claim:

The ornamental design for a shelter, substantially as shown and described.
